PERCY H. D. WALKER, OF MERIDEN, CONNECTICUT, ASSIGNOR TO THE CHARLES PARKER COMPANY, OF MERIDEN, CONNECTICUT, A CORPORATION OF CONNECTICUT.

FIXTURE-LOCK.

1,128,560.

Specification of Letters Patent. Patented Feb. 16, 1915.

Application filed December 13, 1913. Serial No. 806,458.

To all whom it may concern:

Be it known that I, PERCY H. D. WALKER, a citizen of the United States, residing at Meriden, county of New Haven, State of Connecticut, have invented an Improvement 5 in Fixture-Locks, of which the following is a specification.

This invention has for its object to provide a simple and inexpensive lock for wall 10 brackets and fixtures generally and especially adapted for lavatory fixtures, as towel, tumbler, soap and sponge holders, which will hold the fixtures rigidly and securely, may be easily attached, easily re- 15 moved by authorized persons as for refinishing, and which will avoid the use of external screws and the consequent danger of marring the fixtures and will present a perfectly smooth and unbroken surface.

20 With these and other objects in view I have devised the novel fixture attaching means which I will now describe referring to the accompanying drawing forming a part of this specification and using refer- 25 ence characters to indicate the several parts:

Figure 1 is a plan view of a fixture secured in place by my novel lock; Fig. 2 a section on the line 2—2 in Fig. 1, looking in the direction of the arrows; Fig. 3 a view on the line indicated by 3—3 in Fig. 2, looking in the direction of the arrows; Fig. 4 an elevation of the holding plate with the fixture removed; Fig. 5 an edge view of the holding plate; Fig. 6 a view of the cam, detached, and Fig. 7 is a perspective of the key.

10 denotes a wall fixture, which may be of any style and is provided with a base plate 11, 12 the holding plate, 13 the non-pivoted 40 cam and 14 the key. The holding plate is attached to the wall in any suitable manner, as by ordinary wood or expansion screws indicated by 15, and is slightly undercut, as at 16. In one side of the plate is 45 a curved recess 17 to partly receive the non-pivoted cam which is an eccentric and has a portion of its edge beveled, as at 18, and a recess 19 in its upper side to receive the operative portion of the key. The base 50 plate of the fixture is provided in its under- side with an undercut recess 20 correspond- ing in shape with the holding plate and with the portion of the cam not received by the holding plate and is also provided 55 with a sector shaped recess 21 of less depth

than recess 20 to permit the insertion of the key into the recess in the cam and the swinging of the key in opposite directions to oscillate the cam and lock the fixture to the holding plate or to unlock it therefrom. 60 It will be noted that the portion of recess 20, which receives the cam is undercut and that the corresponding portion of the cam is beveled, so that in the locking position, as in Figs. 2 and 3, the base plate is rigidly 65 locked both to the cam and to the holding plate and cannot be detached therefrom until the cam has been oscillated to the unlock- ing position.

The operation is as follows: The holding 70 plate is first secured rigidly in place and need never be disturbed. The cam is laid in the recess in the base plate with the re-cess 19 in the cam in the position indicated by dotted lines in Fig. 3. The base plate 75 with the cam in the recess therein is then placed over the holding plate, the key is passed through recess 17 in the base plate and inserted in the recess in the cam and the cam is turned toward the position shown 80 in full lines in Fig. 3, the effect of which is to force both the cam and the base plate into locking relation with the holding plate. In the case of hotel fixtures and wherever there is danger of unauthorized removal, 85 keys are only allowed in the possession of those authorized to use them, as, should it be desirable to remove fixtures for refinishing. Under the ordinary conditions of use my novel lock will hold the fixtures rigidly 90 in place and will prevent their removal ex- cept by a person having a key.

Having thus described my invention I claim:

1. A fixture lock comprising a fixed hold- 95 ing plate having an undercut edge, a cam member engaging the opposite edge of said plate, a base plate having a recess to receive said holding plate and cam member, said recess having one wall undercut to coop- 100 erate with the undercut edge of said holding plate and an opposite wall engaged by said cam member, and said base plate having also an opening permitting access to said cam member to operate the same.

2. A fixture lock comprising a fixed hold- 105 ing plate having an undercut edge, a cam member engaging the opposite edge of said plate, said opposite edge being recessed to receive said cam member, a base plate hav- 110

ing a recess to receive said holding plate and cam member, said recess having one wall undercut to coöperate with the undercut edge of said holding plate and an opposite wall engaged by said cam member, and said base plate having also an opening permitting access to said cam member to operate the same.

3. A fixture lock comprising a fixed holding plate having an undercut edge, a cam member engaging the opposite edge of said plate, said cam member having a beveled edge, a base plate having a recess to receive said holding plate and cam member, said

recess having one wall undercut to coöperate with the undercut edge of said holding plate and an opposite wall undercut to coöperate with the beveled edge of said cam member, and said base plate having also an opening permitting access to said cam member to operate the same. 15
20

In testimony whereof I affix my signature in presence of two witnesses.

PERCY H. D. WALKER.
